UNITED STATES PATENT OFFICE.

THOMAS LONG, OF BOSTON, MASSACHUSETTS.

EXPANSIBLE REAMER.

SPECIFICATION forming part of Letters Patent No. 417,360, dated December 17, 1889.

Application filed July 2, 1889. Serial No. 316,363. (No model.)

To all whom it may concern:

Be it known that I, THOMAS LONG, a citizen of the United States of America, and a resident of Boston, in the county of Suffolk 5 and State of Massachusetts, have invented certain new and useful Improvements in Expansible Reamers, of which the following is a full, clear, and exact description.

This invention relates to reamers, taps, and 10 such like tools, and particularly pertains to their adaptation for being expanded in diameter.

The tool of this invention in substance has a cylindrical bore of uniform diameter 15 and a split or splits lengthwise thereof and a core to fit said bore, which is in inner and outer parts, the outer being a tube of an external diameter to fit the bore of the tool and having a lengthwise split or splits and of an 20 external taper, and the inner a plug to fit within and by a movement lengthwise of said tube to expand it and through it the tool containing it in its said bore, all substantially as hereinafter described.

25 In the drawings forming part of this specification the invention is illustrated in connection with a reamer, and Figure 1 is a central longitudinal section of a reamer other than this invention of the ordinary construction, and of the outer part and a side view of the inner part of the core. Figs. 2, 3, and 4 are sections, lines 2 2, 3 3, and 4 4, respectively, Fig. 1.

In the drawings, A is the reamer, having a 35 bore A² of uniform diameter and longitudinal splits A³ A⁴.

B and C are the inner and outer parts of the core. The inner part B is a solid cylindrical plug having a tapering head B³, and 40 the outer part C is a tube having an internal diameter to fit the plug B and its tapering head B², lengthwise splits C², and a normal external diameter corresponding to the diameter of the bore of the tool.

45 C³ is a collar fixed on one end of the tube C and having splits C⁴ across its edge, so as

to be expansible under the expansion of the tube, as hereinafter appears, and the plug B within the tube, end to end, extends through and projects from this collar and its projecting end portion receives a screw-threaded nut D. The core in its normal condition is inserted lengthwise in the bore of the tool, on which, by turning up the screw-nut, the inner part or plug B of the core is drawn into 55 the outer part or tube C, and thereby the same expanded, in turn expanding the drill. Unscrewing the screw-nut releases the core and tool to contraction, respectively.

Having thus described my invention, what I 6c claim, and desire to secure by Letters Patent, is—

1. An expansible tool having a bore A² of uniform diameter and lengthwise split or splits A³, in combination with a core fitting 65 said bore, made in parts B C, outer and inner, the outer C a tube having lengthwise split or splits C² and an internal taper, and the inner B a plug of an external taper fitting and adapted to be moved lengthwise in the 70 tube C, substantially as described, for the purpose specified.

2. An expansible tool having a bore A² of uniform diameter and lengthwise split or splits A³, in combination with a core fitting 75 said bore, made in parts B A, outer and inner, the outer C a tube having lengthwise split or splits C², a split collar C³, held thereon, and an internal taper, and the inner B a plug of an external taper fitting and adapted to be 80 moved lengthwise, and with a screw-nut D screwed onto and having bearing against said collar C³ of said core-tube C, substantially as described, for the purpose specified.

In testimony whereof I have hereunto set 85 my hand in the presence of two subscribing witnesses.

THOMAS LONG.
